United States Patent Office

Des. 208,542
Patented Sept. 12, 1967

208,542

RACING WHEEL

Henry T. Halibrand, 6469 Nancy St.,
Los Angeles, Calif. 90045

Filed Mar. 6, 1967, Ser. No. 6,065

Term of patent 14 years

(Cl. D14—30)

FIG. 2.

FIG. 3.

FIG. 4.

FIG. 5.

FIG. 1 is a front view of a racing wheel embodying my new design;

FIGS. 2 and 3 are sectional views taken to show details of the design, substantially as indicated by lines 2—2 and as indicated by line 3—3, in FIG. 1;

FIG. 4 is a front perspective view of the instant design; and

FIG. 5 is a rear view as indicated by line 5—5 on FIG. 2.

I claim:

The ornamental design for a racing wheel, as shown.
